UNITED STATES PATENT OFFICE

FRED B. PFEIFFER, OF AKRON, OHIO, ASSIGNOR TO SEIBERLING RUBBER COMPANY, OF BARBERTON, OHIO, A CORPORATION OF DELAWARE

MOUNTING FOR CALENDER KNIVES

Application filed April 2, 1929. Serial No. 351,913.

This invention relates to holders for maintaining a gang of knives in spaced relation, for the cutting of sheet material, and particularly plastic rubber compound sheeted 5 on the gum roll of a calender, to divide the sheet into strips of desired width for application to fabric strips passing through the calender.

One object of my invention is to mount the 10 knives on the calender frame in the proper relation to the gum roll, in such manner that they may be applied to the calender and removed therefrom as a group without changing the spacing of the individual knives, thus 15 permitting the ready substitution of another group of knives having a different spacing. In this way considerable time is saved as compared with prior arrangements requiring individual setting of the knives; and less 20 skill and accuracy are required of the calender operator because the knife settings are determined and fixed in advance.

A further object is to provide an improved 25 form of knife-holder in which the knives will be accurately fixed in their desired positions and relations, and may be readily inserted and removed by simple manipulations when desired.

Of the accompanying drawings, Fig. 1 is a 30 vertical sectional view of a rubber calender showing my invention applied thereto in a preferred form.

Fig. 2 is a perspective view of a portion of 35 the knife and holder unit.

Fig. 3 is a vertical section of said unit, 40 partly broken away, together with the cross-bar of the calender frame.

Fig. 4 is a partial rear elevation showing 45 a modification.

In the drawings, 10 is one of the side standards of a three-roll calender including an upper roll 11, a middle or gum roll 12 on which the rubber compound is sheeted from a bank 13 located on the rear side between 50 the two rolls and on which the sheet 33 is then divided into strips 34, and a lower or fabric roll 14 separated from the middle roll by a space for the passage of the fabric strips 55 to which certain of the gum strips 34 are 60 adhesively united. 15 is the cross-bar com-

monly provided on the calender frame for mounting gum knives, and on which I suspend my improved gang knife-holder.

16, 16 are the gum knives or blades, of a 55 form conveniently made in the desired length from old hack-saw blades by grinding off the saw teeth and sharpening the edges, and preferably arranged to cut on both edges, so that when one edge gets dull the knife 60 may be reversed to use the opposite edge. 65 These knives are loosely assembled and maintained at the desired spacing in slots 17 formed in the outstanding flanges of a pair of parallel angle-irons 18, 19 attached to the face of a supporting plate or board 20. Said 70 board and angle irons constitute a holder frame having fixed knife-holding and guiding jaws formed by the sides of the slots 17.

The lower spacing slots 17 are made deeper 75 than the upper ones so that the inner edges of the knives will bottom at the ends of the latter but not the former. The inner edges of the knives are supported by a backing bar 21 affixed to said plate just above the flange 80 of the lower angle-iron 19, this bar being 75 made of resilient material such as vulcanized soft rubber and serving to take up any slack in the individual knife mountings, to avoid excessive individual knife pressures against the gum roll and to equalize any lack of uniformity in the amount of projection of the several knives. The lower ends of the knives 85 may be brought substantially to the same level by means of stop blocks 22 affixed to said knives near their upper ends, one on either side, and resting on the flange of the upper spacing bar 18. A clamping bar 23, 90 adjustably secured by end bolts 24 to the supporting plate 20, overlies the knives 16 just below the flange of the upper spacer bar 95 18 and collectively locks or retains said knives in the spacer bars by engagement with their exposed outer edges.

At each end of the supporting plate 20 is fastened a downwardly-open hook 25 having an upper attaching jaw 26 engaging the upper edge of said plate, and a lower jaw 27 provided with an adjustable clamping screw 28 engaging its lower edge, for detachably securing said hook to the plate 20 95

in a position projecting forwardly therefrom, or on the side opposite to that on which the knife-blades 16 are mounted. These two hooks serve for demountably suspending the 5 multiple knife and holder unit from the calender frame-bar 15, so that the knives are movable in unison into and out of operative relation with the work. Each of the hooks 25 has fixed to the lower end of its free 10 member an arm 29 projecting at right-angles thereto and formed near its free end with an upwardly-open notch 30 for detachably suspending a weight 31. This weight, being spaced forward from the fulcrum bar 15, 15 exerts considerable leverage on the knife-holder and furnishes pressure for forcing the knives 16 through the gum sheet on the roll 12, and against said roll, to divide the sheet 20 33 into strips 34.

20 In the modification represented in Fig. 4, I show an alternative means for limiting the endwise movement of the knife blades 16 when loosely mounted in the holder before setting up the clamping bar 23, said means 25 consisting of a rod 32 common to the several knife blades and occupying holes formed therein, said rod resting on the flange of the upper spacing bar 18. This modified arrangement enables the knife blades to be 30 applied to and removed from the holder as a group, but it is considered less desirable than the form shown in the other views, which permits any single knife blade to be 35 inserted or removed without disturbing the others.

In the use of this apparatus, a number of 40 these gang knife and holder units, in which the knives have different spacings corresponding to the various widths and spacings 45 of the gum-strips which it is desired to cut from the sheet formed by the calender, are kept on hand, and when any change to a different width or spacing of strips is to be made it is a very simple matter to detach 50 the holder then mounted on the calender, lift it as a unit out of the space between the cross-bar 15 and the top and middle calender rolls, until the holder is clear of said cross-bar, and then substitute a different holder 55 having the desired new spacing of knives. Before removal, the detachable weights 31 are removed and are thereafter replaced when the substitution has been effected. The hooks 25 are mounted with a uniform spacing on the different knife-holders, and suitable adjustable end stops (not shown) may be provided on the cross-bar 15 for fixing the lateral position of the knife-holder, these stops being changed whenever it is desired 60 to shift said lateral position. It will be evident that the use of my invention on calenders devoted to strip work, where the sizes and spacings are periodically changed, results in a saving of time proportionate to the 65 number of changes made, as compared with

the usual system of individual mounting of knives upon the cross-bar 15 which requires each knife to be set separately, the calender meanwhile running idle and the time of the operator being consumed in making a 70 lengthy adjustment instead of turning out work.

The described means of detachably mounting the individual knife blades in the holder also facilitates the substitution and reversal 75 of knives when their edges become dull, by another operator whose time may be devoted to that work.

It will be understood that various modifications of structure and arrangement in addition to the one described may be effected 80 without departing from the scope of my invention as defined in the claims.

I claim:

1. In combination, a rubber calender having 85 a gum roll, a gang of knives held in fixed relation to each other, and movable in unison into and out of cooperative relation with the gum roll, and means for hooking and unhooking said knives as a group, on and from 90 the calender.

2. In combination, a rubber calender having 95 a frame cross-bar and a gum roll, a knife holder, a gang of knives mounted in said holder and coacting with the gum roll for dividing the rubber sheet on said roll into strips, and means operable as a unit and attachable at different positions along the cross-bar for detachably connecting the knife holder 100 with said cross-bar.

3. In combination, a rubber calender having 105 a frame cross-bar and a gum roll, a knife holder, a gang of knives mounted in fixed relation on said holder, and a hook structure for detachably pivoting said holder on said cross-bar.

4. A multiple knife and holder unit for 110 rubber calenders comprising a knife holder, a gang of knives mounted on said holder, and a plurality of hooks projecting from said holder on the side opposite to the active cutting edges of the knives and open downwardly, for detachably mounting said holder on the knife-supporting portion of the calender frame.

5. A multiple knife and holder unit comprising 115 a holder, a gang of knives detachably fixed in spaced relation on one side of said holder, and means projecting from the opposite side of said holder for demountably suspending said knife and holder unit in operative relation to the work.

6. A multiple knife and holder unit comprising 120 a holder, a gang of knives fixed in spaced relation on one side of said holder, means including a downwardly-open hook projecting from the opposite side of the holder for demountably suspending the unit in operative relation to the work, and an arm 125 projecting from said hook and having means 130

for detachably suspending a weight to increase the knife pressure against the work.

7. A multiple knife and holder unit comprising a gang of knife blades, a holder formed with guide jaws for maintaining said blades in spaced relation, and an adjustable clamping device common to said blades and overlying their exposed edges, for locking them in place.

10 8. A multiple knife and holder unit comprising a support, a plurality of spacer bars mounted on said support and formed with knife-blade slots, a gang of knife blades loosely mounted in spaced relation in said slots, 15 and means for clamping said knife blades in place.

9. A multiple knife and holder unit comprising a support, a pair of parallel spacer bars mounted thereon and formed with knife-blade slots, a gang of knife blades occupying slots in the respective spacer bars, a clamping bar common to said knife blades, engaging their exposed edges and located between the two spacer bars, and means for bolting said 25 clamping bar to said support.

10. A multiple knife and holder unit comprising a gang of knife blades, a holder having means for maintaining said blades in spaced relation, individual lateral stop projections on the blades for limiting their endwise movement in the holder, and means for 30 clamping said blades in place.

11. A multiple knife and holder unit comprising a holder having suspending means on its upper portion, a gang of knife blades mounted in said holder and each having holder-free lower cutting ends, and means overlying the exposed back edges of the blades for 35 detachably clamping said blades in the holder.

12. A multiple knife and holder unit comprising a holder having knife-spacing means, a resilient backing bar thereon, a gang of knives whose inner edges rest on said bar, and 40 means acting edgewise of the knives for detachably securing said knives in said holder.

13. A multiple knife and holder unit comprising a holder having upper and lower slotted spacer bars, a gang of reversible knife 45 blades loosely received in the slots of the respective spacer bars and having means for limiting their endwise movement, each of said blades being sharpened on both edges, a common clamping bar detachably bolted to the holder between said spacer bars and located adjacent to the upper one, and a resilient 50 backing bar located between said spacer bars adjacent to the lower one, for supporting the inner edges of the blades.

60 In witness whereof I have hereunto set my hand this 30th day of March, 1929.

FRED B. PFEIFFER.
